UNITED STATES PATENT OFFICE.

ANTON VAN VEEN, OF WEST HARTFORD, CONNECTICUT, ASSIGNOR TO THE FULLER BRUSH COMPANY, OF HARTFORD, CONNECTICUT, A CORPORATION OF CONNECTICUT.

MACHINE FOR TWISTING WIRES WITH MATERIAL THEREBETWEEN.

Application filed July 3, 1926. Serial No. 120,358.

This invention relates to the class of machines employed for making dust mops or similar structures by securing strands of cotton or other fibrous material between the 5 members of a twisted wire core, and an object of the invention, among others, is the production of a machine of this class that shall be particularly efficient in operation.

One form of machine embodying the invention, and in the construction and use of which the objects herein set out, as well as others, may be attained is illustrated in the accompanying drawings, in which—

Figure 1 is a top view of this improved 15 machine.

Figure 2 is a view in lengthwise horizontal section on a plane denoted by the dotted line 2—2 of Figure 3.

Figure 3 is a view in front elevation, scale 20 enlarged, of the right hand end and upper part of the machine.

Figure 4 is a view in vertical section on a plane denoted by the dotted line 4—4 of Figure 9.

Figure 5 is a top view, partly in section, of the left hand end of the machine, illustrating the construction of the tail stock.

Figure 6 is a front view of the mechanism shown in Figure 5 with the frame broken 30 away.

Figure 7 is a view in cross section on a plane denoted by the dotted line 7—7 of Figure 5.

Figure 8 is a view in cross section on a 35 plane denoted by the dotted line 8—8 of Figure 5.

Figure 9 is a view in cross section on a plane denoted by the dotted line 9—9 of Figure 3.

Figure 10 is a similar view on a plane denoted by the dotted line 10—10 of Figure 3.

Figure 11 is a view in lengthwise horizontal section on a plane denoted by the dotted line 11—11 of Figure 3.

45 This invention relates more especially to the mechanism for positioning and for twisting wires to secure the mop material therein. In the structure illustrated in the drawings herein certain parts are shown but are not referred to, as they do not comprise a part of the present invention, and yet they are

included in the machine structure as a whole and are specifically set forth in copending applications filed concurrently herewith, filed July 3, 1926, and having respectively 55 the Serial Nos. 120,357, 120,359 and 120,360.

In the accompanying drawings the numeral 10 denotes the end portions of the frame of this improved machine, and 11 a beam secured to and connecting the end portions at the upper parts thereof, the bottom parts of the frame not being shown herein. A head stock in the form of a bracket 12 is mounted upon the beam 11 at one end of the machine and comprises two uprights 13 for 60 the support of twisting mechanism that comprises a clamp sleeve 14 rotatably mounted in said uprights and having a flared mouth to receive the enlarged end of chuck jaws 15 of spring formation connected at their inner 65 ends and secured to a spindle 16 mounted for endwise movement within the sleeve to draw said jaws into said flared mouth and thereby close the jaws together to clamp wires between them. An adjusting block 17 formed 70 in halves is attached to the clamp sleeve 14 as by means of interengaging screw threads, and a clamp lever support 18 is secured to said block as by means of interlocking flanges, as shown in Figure 4 of the drawings. Each of the clamp levers 19 is pivotally mounted in a slot in the support 18, the heels of said levers being adapted to thrust against clamping lugs 20 projecting 75 from opposite sides of the spindle 16 and 80 within the support 18. The free ends of said levers extend into a recess in a jaw clamping collar 21 mounted for reciprocating movement on the sleeve 14 and operated by means of a jaw clamping slide 22 mounted for 85 reciprocating movement on a tubular support 23 located in the bracket 12 or head stock of 90 the machine.

The spindle 16 is rotatably supported at its rear end in a hollow shaft 24 mounted in a 95 bushing in an end 10 at this end of the frame, a driving pulley 25 being secured to the shaft 24 and adapted to receive a belt 26 that may be driven from any suitable source of power. Contained within this pulley is one member of 100 a roller clutch of any well known construction, this clutch comprising a bearing ring 27

to receive the thrust of the clutch rollers (see Figure 4). The other clutch member 28 is splined to the spindle 16 to permit the latter the endwise movement hereinbefore mentioned but to effect its rotation. The clutch is actuated by means of a clutch actuator in the form of a housing 29 inclosing spiral springs, one end of each of which springs is secured to the housing and the other end to the clutch member 28, so that the tendency of the springs is to impart rotating movement to said housing and said member in opposite direction, the housing having fingers projecting between the rollers to move them into or out of clutching position. The action of the springs is to move the rollers into clutching position, and the parts being in rotation a shoulder 30 on the housing or actuator striking the end of a clutch releasing lever 31 stops rotation of said actuator, and the spindle still traveling forwardly the clutch rollers are released, thereby stopping rotation of the spindle 16. The open end of the housing is closed by a flange on the clutch member 28 and to which flange one end of each of the clutch springs hereinbefore referred to is secured.

The hollow shaft 24 has a pulley 32 secured thereto that receives a belt 33 for driving other parts of the machine and including feed rollers for mop material to be hereinafter referred to. The spindle 16 is forced endwise to unclamp the chuck jaws 15 by a spring 34 located in a recess in the end of the spindle and thrusting against a plunger that is forced against a cap within the end of the pulley 32, and as shown in Figure 4 of the drawings.

The jaw clamping collar 21 is actuated as by means of a hand lever 35 secured to a rock shaft 36 mounted in the bracket 12 on the head stock, the end of said lever having teeth to mesh with the teeth of a rack on the slide 22 that has fingers extending into an annular groove in the collar 21, and as shown in Figures 3 and 4 of the drawings. The lower end of the rock shaft 36 has a pinion the teeth of which mesh with the teeth of a rack sleeve 37 secured to one end of a connecting rod 38 extending to a clamping mechanism of a tail stock to be hereinafter described.

50 A wire centering mechanism comprises centering fingers 39—40 pivotally supported on one of the uprights 13 of the head stock, and as shown in Figure 9 of the drawings, these fingers being operatively connected by intermeshing teeth, the finger 40 being connected by a link with an arm 41 secured to the end of a rock shaft 42 having a cam slot 43 that receives the inner end of a pin 44 projecting inwardly from the slide 22, and as shown in Figure 11 of the drawings.

It thus will be seen that when the handle 35 is operated to actuate the levers 19 to clamp wires in the chuck, the fingers 39 and 40 will be simultaneously operated to center said wires, said fingers engaging said wires on op-

posite sides and moving them toward each other, the cam slot being so arranged that the wires will be centered before the chuck jaws are closed together to fully clamp said wires.

70 A tail stock 45 is mounted on the beam 11 at the opposite end of the machine from the head stock, said tail stock being mounted for a limited sliding movement on the beam. A stationary clamping jaw 46 is secured to the tail stock and a movable clamping jaw is secured to a clamping jaw lever 47 pivotally mounted on the tail stock and operated as by means of a cam 48 on a shaft 49 mounted in the tail stock and having a pinion at its lower end, the teeth of which are engaged with the teeth of a rack sleeve 50 secured to the connecting rod 38 at the end thereof opposite to the rack sleeve 37.

75 Centering fingers 51—52 are secured at the ends of rock shafts 53—54 mounted in the tail stock, the shaft 53 having a spring to rock it in one direction and the shaft 54 having an arm 55 for rocking said shaft in a direction opposite to that caused by said spring, the fingers 51 and 52 having interengaging teeth 80 whereby when one is operated the other is likewise operated. The arm 55 is engaged by a finger 56 on a shaft 57, which shaft has a projecting toe 58 engaged by a spring pressed 85 plunger 59 mounted in the tail stock and operated in one direction by a cam 60 on the shaft 49.

90 In the operation of the machine the wires are intermittently delivered in any suitable manner, as from a rack 61 from which they drop into a space between the jaws 15 on the live spindle of the head stock and between the jaws 46 and that on the lever 47 of the tail stock, the bottom wire from the rack falling into a groove on a table 62. A layer of 95

mop material 63 composed of strands of cotton or other threads is projected across said wire on the table, by mechanism not herein specifically described, and during a pause in the feed of such mop material a second wire is dropped from the rack 61 on top of the mass of material. The hand lever 35 being now operated by swinging it to the position shown in dotted lines in Figure 1 of the drawings, the slide 22 is moved to the right and by reason of the pin 44 engaging the cam slot 43 the rock shaft 42 is rotated to move the centering fingers 39 and 40 toward each other to center the wires hereinbefore mentioned. This movement of the lever 35 rocks the shaft 36 and thereby moves the rack sleeve 37 and rod 38 toward the right, and by reason of the connection of said rod with the pinion on the shaft 49 said shaft is turned 110

115 and the cam 60 thereon operates the shaft 57 and thereby the shafts 53 and 54 to move the fingers 51 and 52 toward each other to center the wires at the tail stock, these centering fingers at the head and tail stocks operating 120

substantially simultaneously. This is the preliminary operation of clamping the wires. Immediately following this centering operation the movement of the hand lever 35 described operates the slide 22 to actuate the clamping collar 21, thereby moving the spindle 16 longitudinally against the tension of its spring and closing the jaws 15 upon the two centered wires. At the same time the rotation of the shaft 49 in the tail stock, in the manner just hereinbefore described, causes the cam 48 to operate the clamp lever 47 to clamp the centered wires, and immediately following the clamping of the wires the form of the slot 43 is such as to return the centering fingers 39 and 40 to their released positions, or move them away from the wires, this reverse movement of the centering fingers taking place between the time that the clamping jaws begin to grip the wires and the time that the full grip takes place. The spindle being now operated as by connecting the clutch members 27—28, this by means of the clutch rollers, the spindle 16 will be rotated to twist the wires and thus secure the material therein. It will be understood that previous to this twisting operation and after the wires have been centered and clamped, mechanism not specifically herein shown and described, but as embodied in my copending application S. No. 120,360 will operate to cut the mass of material engaged with the wires and sever it from the main portion thereof.

After the twisting operation the movement of the lever 35 to an opposite position, and as shown in full lines in Figure 1, will release the clamping jaws at both ends of the machine in a manner that will be readily understood from the foregoing description, the spring 34 of the spindle 16 moving said spindle to loosen the jaws 15, and this movement of the lever 35 through the connecting rod 38 operating the shaft 49 and the cam 48 thereon to release the clamping jaw on the lever 47.

If desired, a manually operated shaft 64 may be mounted in the tail stock in toothed engagement with the shaft 49 and having a hand lever 65 operated as by means of a handle 66, as shown in Figures 5 to 8 of the drawing.

As a means for controlling starting and stopping operations of the spindle and twisting mechanism a starting lever handle 67 is pivotally mounted on the beam 11 and with its opposite end in the path of movement of a stopping rod 68 slidably mounted on the beam in the path of movement of the tail stock 45, said rod being forced by a spring to move in a direction opposite to that caused by the tail stock. This handle lever is held in contact with a clutch actuating rod 69 slidably mounted in the bracket 12, as shown in Figure 2 of the drawings, said rod being forced into contact with the lever by means of a spring on the rod, and a detent 70 on a detent lever 71 holds said lever against movement under the influence of said spring, as shown in Figures 2 and 4 of the drawings. A clutch actuating lever 72 is pivotally mounted on the bracket 12 with one end extending into a socket in the rod 69 and its opposite end being pivotally attached to a spring pressed plunger 73 located in an extension from the clutch releasing lever 31 hereinbefore described.

The handle lever 67 is released by a downward swinging movement of the table 62 operated by a foot treadle, (not herein shown but illustrated and described in my copending application S. No. 120,357, filed concurrently herewith) said table forcing a plunger 74 downwardly, the detent lever 71 being pivotally attached at one end to said plunger and thereby swung on its pivot to disengage the detent 70 from said lever 67.

The tail stock, as hereinbefore mentioned, has a limited sliding movement on the beam 11, it being remarked that as the wires are twisted they are shortened, and this causes a movement of the tail stock toward the head stock or bracket 12. In this movement of the tail stock it comes in contact with the rod 68 and moves said rod into contact with the handle lever 67, swinging said lever on its pivot and moving it out of the path of movement of the detent 70 and against the force of a spring (not shown) acting upon the plunger 74. The detent thereupon moves upwardly into the path of said lever to hold it against movement upon release of pressure on the rod 68 when the tail stock moves in the opposite direction to that just described. This movement of the lever 67, through the rod 68 and lever 72, operates the clutch releasing lever 31, placing its end in the path of the shoulder 30 on the housing 29 to thereby actuate the clutch and stop rotation of the winding spindle.

When the tail stock has been moved forward by the shortening of the wires in twisting, as hereinbefore described, upon release of the jaws on the tail stock to release the wires the tail stock is moved backwardly under the influence of a weight secured to the lower end of a cord or strap 75.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to other uses than those above set out.

I claim—

- Mechanism for twisting wires with material therebetween and including a twisting spindle comprising chuck jaws, means for supplying wires to said jaws, means for cen-

tering the wires between the jaws, means for closing said jaws, a connection between said centering means and jaw closing means for simultaneous operation of both, and means for holding the opposite ends of the wires.

2. Mechanism for twisting wires with material therebetween and including a twisting spindle comprising chuck jaws, means for supplying wires to said jaws, means for centering said wires between the jaws, manually operated means for closing said jaws, a connection between said centering means and jaw closing means for simultaneous operation of both, and means for holding the opposite ends of the wires.

3. Mechanism for twisting wires with material therebetween and including a twisting spindle comprising chuck jaws, means for supplying wires to said jaws, a pair of centering fingers pivotally mounted adjacent to the jaws to engage wires on opposite sides thereof to center them between the jaws, means for closing said jaws, a connection between said fingers and jaw closing means for simultaneous operation of both, and means for holding the opposite ends of the wires.

4. Mechanism for twisting wires with material therebetween and including a twisting spindle comprising chuck jaws, means for supplying wires to said jaws, a pair of centering fingers pivotally mounted and having a connection to simultaneously swing them in opposite directions to engage wires on opposite sides thereof to center them between the jaws, means for closing the jaws, a connection between one of said fingers and the jaw closing means for simultaneous operation of both fingers, and means for holding the opposite ends of the wires.

5. Mechanism for twisting wires with material therebetween and including a twisting spindle comprising chuck jaws, means for supplying wires to said jaws, a pair of centering fingers pivotally mounted and having a toothed connection to simultaneously swing said fingers in opposite directions to engage wires on opposite sides thereof to center them between the jaws, means for closing said jaws, a connection between one of said fingers and the jaw closing means for simultaneous operation of both fingers, and means for holding the ends of the wires.

6. Mechanism for twisting wires with material therebetween and including a twisting spindle comprising chuck jaws, means for supplying wires to said jaws, a pair of centering fingers pivotally mounted, a rock shaft operatively connected with said fingers to swing them in opposite directions to engage wires on opposite sides thereof to center them between the jaws, means for closing said jaws, a connection between said jaw closing means and said shaft for simultaneous operation of both, and means for holding the opposite ends of said wires.

7. Mechanism for twisting wires with material therebetween and including a twisting spindle comprising chuck jaws, means for supplying wires to said jaws, a pair of centering fingers pivotally mounted, a rock shaft having an arm operatively connected with said fingers to swing them in opposite directions to engage wires on opposite sides thereof to center them between said jaws, means for closing said jaws, a connection between said jaw closing means and said shaft for simultaneous operation of both, and means for holding the opposite ends of said wires.

8. Mechanism for twisting wires with material therebetween and including a twisting spindle comprising chuck jaws, means for supplying wires to said jaws, a pair of centering fingers pivotally mounted and having a toothed engagement to swing said fingers in opposite directions to engage wires on opposite sides and center them between said jaws, a rock shaft having an arm operatively connected with one of said fingers, means for closing said jaws, a connection between said jaw closing means and said shaft for simultaneous operation of both, and means for holding the opposite ends of said wires.

9. Mechanism for twisting wires with material therebetween and including a twisting spindle comprising chuck jaws, means for supplying wires to said jaws, a pair of centering fingers pivotally mounted, a rock shaft operatively connected with said fingers to swing them in opposite directions to engage the wires on the opposite sides thereof to center them between the jaws, a slide operatively connected with said rock shaft to swing it in opposite directions, means for operating said slide, a connection between said slide and said jaws for operation of the latter, and means for holding the opposite ends of said wires.

10. Mechanism for twisting wires with material therebetween and including a twisting spindle comprising chuck jaws, means for supplying wires to said jaws, a pair of centering fingers pivotally mounted, a rock shaft operatively connected with said fingers to swing them in opposite directions to engage wires on opposite sides thereof to center them between the jaws, said shaft having a cam slot, a slide having a pin extending into said slot to swing said shaft in opposite directions, means for operating said slide, a connection between said slide and said jaws for operation of the latter, and means for holding the opposite ends of said wires.

11. Mechanism for twisting wires with material therebetween and including a twisting spindle comprising chuck jaws, means for supplying wires to said jaws, a pair of centering fingers pivotally mounted, a slide operatively connected with said jaws to operate them, a connection between said slide and said fingers to swing the latter in oppo-

- site directions to engage wires on opposite sides thereof and center them between said jaws, said slide having a toothed rack, a pivotally mounted hand lever having a toothed engagement with the teeth of said rack to operate said slide, and means for holding the opposite ends of said wires. 12. Mechanism for twisting wires with material therebetween and including a twisting spindle comprising a set of chuck jaws, means for supplying wires to said jaws, means for opening and closing said jaws, a tail stock having clamping jaws to receive said wires, and a connection between the jaws on the tail stock and the means for opening and closing the jaws of the spindle for simultaneous operation of both sets of jaws. 13. Mechanism for twisting wires with material therebetween and including a twisting spindle comprising a set of chuck jaws, means for supplying wires to said jaws, means for opening and closing said jaws, a tail stock having clamping jaws to receive said wires, means for opening and closing said jaws, and a connection between both of said jaw opening and closing means whereby operation of either will operate both sets of jaws. 14. Mechanism for twisting wires with material therebetween and including a twisting spindle comprising a set of chuck jaws, means for supplying wires to said jaws, manually actuated means for operating said jaws, a tail stock having clamping jaws to receive said wires, and a connection between the jaws on the tail stock and said manually operated means for simultaneous operation of the jaws appurtenant to the spindle and on the tail stock. 15. Mechanism for twisting wires with material therebetween and including a twisting spindle comprising a set of chuck jaws, means for supplying wires to said jaws, manually actuated means for operating said jaws, a tail stock having a set of clamping jaws to receive said wires, manually actuated means for operating said jaws, and a connection between both sets of said jaws whereby operation of either will operate both sets of said jaws. 16. Mechanism for twisting wires with material therebetween and including a twisting spindle comprising a set of chuck jaws, means for supplying wires to said jaws, a tail stock having a set of clamping jaws to receive said wires, means for operating one of said sets of jaws, and a connection between one of said sets of jaws and the means for opening and closing the opposite set for simultaneous operation of both sets of jaws. 17. Mechanism for twisting wires with material therebetween and including a twisting spindle comprising a set of chuck jaws, means for supplying wires to said jaws, a tail stock having a set of jaws to receive said wires, manually operated means for opening and closing one of said sets of jaws, and a connection between said manually operated means and the opposite set of jaws for simultaneous operation of both. 18. Mechanism for twisting wires with material therebetween and including a twisting spindle comprising a set of chuck jaws, means for supplying wires to said jaws, a tail stock having a set of clamping jaws to receive said wires, a tail stock jaw operating shaft, a toothed rack engaged with said shaft, a toothed rack appurtenant to said spindle, a connection between said racks for simultaneous operation of both, a connection between said rack appurtenant to the spindle and the jaws thereon for operation of the latter, and means for operating one of said racks. 19. Mechanism for twisting wires with material therebetween and including a twisting spindle comprising a set of chuck jaws, means for supplying wires to said jaws, a tail stock having a set of clamping jaws to receive said wires, a tail stock jaw operating shaft, a toothed rack engaging said shaft, a toothed rack appurtenant to said spindle, a connection between said racks for simultaneous operation of both, a connection between said rack appurtenant to the spindle and the jaws thereof for operation of the latter, and means for operating the rack appurtenant to the spindle. 20. Mechanism for twisting wires with material therebetween and including a twisting spindle comprising a set of chuck jaws, means for supplying wires to said jaws, a tail stock having clamping jaws to receive said wires, a tail stock jaw operating shaft, a toothed rack engaged with said shaft, a toothed rack appurtenant to said spindle, a connection between said racks for simultaneous operation of both, a connection between said rack appurtenant to the spindle and the jaws thereof for operation of the latter, and manually operated means for actuating one of said racks. 21. Mechanism for twisting wires with material therebetween and including a twisting spindle comprising a set of chuck jaws, means for supplying wires to said jaws, a tail stock having a set of clamping jaws to receive said wires, a tail stock jaw operating shaft, a toothed rack engaging said shaft, means for operating said rack, a toothed rack appurtenant to said spindle, means for operating said rack, and a connection between said racks whereby operation of either will simultaneously operate both sets of clamp jaws. 22. Mechanism for twisting wires with material therebetween and including a twisting spindle comprising a set of chuck jaws, a shaft having toothed members, means for operating said shaft, a connection between one of said members and said chuck jaws for operation of the latter, a tail stock having a set of clamping jaws, and a connection between the other of said members and said clamping jaws for operation of the latter.
